ABSTRACT

A roughing machine for roughing the margin of an upper of a shoe assembly comprised of a last having an insole on its bottom and the upper mounted thereon with the upper margin lying against and being secured to the insole periphery. The shoe assembly is mounted to a slide that is reciprocal in a rotatable turntable. The machine has a roughing tool for roughing the margin as the margin is moved past the roughing tool by alternate rotations of the turntable and movements of the slide in the turntable. The machine is so constructed that the roughing tool can automatically sense and follow the contour of the shoe assembly as the upper margin portions are moved past the roughing tool to enable the roughing tool to be automatically located in the proper positions for roughing the upper margin.

**MACHINE FOR ROUGHING THE MARGIN OF AN
UPPER OF A SHOE ASSEMBLY**

**BACKGROUND AND SUMMARY OF THE
INVENTION**

This invention is an improvement of the type of roughing machine illustrated in British Patent Specification No. 1,174,008. The prior machine has a shoe assembly support which mounts a shoe assembly that includes a last having an upper, with a margin to be roughed, mounted thereon. The upper margin is roughed or abraded so that it may better adhere to an outsole that is subsequently attached to the bottom of the shoe assembly. The shoe assembly support is moved past a roughing tool to enable the roughing tool to rough the upper margin. The tool is located in the proper roughing position, while roughing the toe and heel portions of the upper margin, by being urged downwardly towards the shoe assembly until tines engage the upper margin and by being urged forwardly towards the shoe assembly until a sensing finger engages the shoe assembly. The forward-rearward position of the roughing tool, while roughing side portions of the upper margin, is controlled by a cam follower arrangement.

A first aspect of this invention is concerned with so improving the prior machine as to enable the position of the roughing tool to be properly positioned for roughing during the roughing of the side portions of the upper margin as well as the heel and/or toe portions of the upper margin by the coaction of the sensing finger with the side of the shoe assembly. This is accomplished by providing a motor driven slide in the machine to which the roughing tool is mounted for heightwise movement with respect to the slide and for forward-rearward movement in unison with the slide. A bar, having the sensing finger mounted to its front, is mounted to the slide for forward-rearward movement. A control so interconnects the motor and the bar that a positioning of the bar forwardly of a median position in the slide causes the motor to move the slide forwardly, a positioning of the bar rearwardly of the median position in the slide causes the motor to move the slide rearwardly, and a positioning of the bar in the median position in the slide renders the motor ineffective to move the slide forwardly or rearwardly. An operating device is actuatable to yieldably urge the bar forwardly of the median position in the slide. This arrangement enables the sensing finger to follow the contour of the side of the shoe assembly during the movement of the shoe assembly past the sensing finger and enables the roughing tool to accurately and rapidly move forwardly and rearwardly in accordance with the contour of the side of the shoe assembly so as to always be positioned, in forward-rearward directions, in proper positions for roughing the upper margin portions that are moving past the roughing tool. In order to enable the roughing tool to be in rearward out-of-the-way position during the placement of the shoe assembly on the shoe assembly support, a mechanism is provided for initially deactuating the operating device to thereby render the motor effective to move the slide to a rearward position.

In the prior machine, there is a tendency for the roughing tool to dig a groove into the portion of the upper margin that it engages when it is lowered against the shoe assembly due to the shoe assembly being sta-

tionary for a period of time after the roughing tool has been lowered. A second aspect of this invention is concerned with an arrangement for ensuring that the upper margin is not stationary long enough for the roughing tool to dig the groove when the roughing tool is lowered against the upper margin. This is accomplished by mounting the roughing tool for heightwise movement in a tool mount. The tool mount is mounted to a shaft, the tines being mounted to the front of the shaft. A yieldable motor connected to the roughing tool effects heightwise movement of the roughing tool with respect to the tool mount and initially retains the roughing tool in an upper position on the tool mount above the tines. After the tines have been lowered into engagement with a portion of the upper margin, the motor moves the roughing tool into engagement with the upper margin and the shoe assembly support is so moved as to move other portions of the upper margin past the roughing tool.

In the prior machine, the tines are so mounted as to rock during their engagement with the upper margin during the movement of the upper margin past the tines so that the plane of the bottom of the tines stays parallel to the planes of the upper margin portions engaged by the tines. A connection between the tines and the roughing tool enables the roughing tool to rock in the same direction and to the same extent as the tines in response to the rocking of the tines so that the central plane of the roughing tool is maintained at right angles to the plane of the portions of the upper margin being roughed. A third aspect of the invention is concerned with an improved construction for rocking the roughing tool in correlation with the rocking of the tines.

The construction of the third aspect of the invention includes a housing to which the roughing tool is mounted. The housing is mounted to the shaft, to whose front the tines are mounted, for swinging movement about the axis of the shaft and is moveable about the shaft axis by a motor. A cam on the shaft bears against a first end of a lever that is pivoted to the housing. The second end of the lever bears against the valve spool of a valve mounted to the housing, the valve spool being yieldably urged against the second lever end. The valve and the motor are so connected that the motor does not move the housing when the valve spool is in a median position in the body of the valve. The connection between the valve and motor causes a movement of the valve spool by the cam, in response to swinging movement of the shaft about its axis, in opposite directions from its median position to cause the motor to swing the housing, and thus the roughing tool, in corresponding directions about the shaft axis.

The bottom of a particular portion, usually the toe portion, of the shoe assembly is somewhat rounded and relatively convex as compared with the bottom of the remainder of the shoe assembly. Therefore, if the roughing tool is located the same distance forwardly of the sensing finger when roughing the particular portion of the upper margin as when it is roughing the other portions of the upper margin, the roughing tool will rough the particular portion of the upper margin too far inwardly of its outer periphery. A fourth aspect of this invention is concerned with a construction for overcoming this difficulty.

The construction of the fourth aspect of the invention includes the mounting of the roughing tool to the housing for forward-rearward movement and an ar-

angement for normally maintaining the roughing tool in a forward position with respect to the housing and thus of the sensing finger. An adjusting mechanism is provided that is effective, with the particular portion of the upper margin is moving past the roughing tool, to move the roughing tool rearwardly with respect to the housing and thuswith respect to the sensing finger.

In the prior machine, an oval gear wheel causes the shoe assembly support to move the shoe assembly past the roughing tool in such a manner that the heel and toe portions of the shoe assembly revolve approximately 180 degrees about an upright axis during the respective movements of the heel and toe portions of the upper margin past the roughing tool and the side portions of the upper margin move substancially rectilin-early past the roughing tool between said revolving movements and during the movements of the side portions of the upper margin past the roughing tool. The motion imparted to the shoe assembly support by the oval gear is identical regardless of the length of the shoe assembly being roughed. Ideally the axis about which the shoe assembly revolves during the roughing of the heel and toe portions of the upper margin should respectively be at the approximate centers of the curvature of the heel and toe portions of the upper margin. A fifth aspect of the invention is directed to an improved construction which provides an adjustable arrangement enabling a shoe assembly to respectively revolve about the approximate centers of the curvature of the heel and toe portions of the shoe assembly when the roughing tool is roughing the heel and toe portions of the shoe assembly regardless of the length of the shoe assembly.

In accordance with the fifth aspect of the invention, the mechanism for moving the portions of the upper margin of the shoe assembly past the roughing tool includes a turntable that is rotatable about an upright axis. A slide is mounted to the turntable for reciprocal movement on the turntable between two end positions on the turntable and the shoe assembly support is mounted to the slide. The machine is so constructed that the turntable rotates 180 degrees about the upright axis when the slide is at each of its end positions to move the heel and toe portions of the upper margin past the roughing tool and the slide is moved from one end to the other of its end positions between rotations of the turntable to move the side portions of the upper margin past the roughing tool. In order to enable the shoe assembly to revolve with the turntable about an axis that coincides with the approximate centers of the curvature of the heel and toe portions of the shoe assembly, an adjusting mechanism is provided that adjusts the spacing between the end positions of the slide on the turntable an amount that is proportional to the length of the shoe assembly.

BRIEF DESCRIPTION OF THE DRAWINGS

FIG. 1 is a side elevation of the machine;

FIG. 2 is a view taken along the line 2—2 of FIG. 1;

FIG. 3 is an isometric view of the machine, looking from the front of the machine;

FIG. 3A is an isometric view of a toe stop in the machine;

FIG. 4 is a plan view of the turntable and the slide mounted to the turntable;

FIG. 5 is a section taken along the line 5—5 of FIG. 4;

FIG. 6 is a section taken along the line 6—6 of FIG. 4;

FIG. 7 is a bottom view of the slide that is mounted to the turntable;

FIG. 8 is a view taken along the line 8—8 of FIG. 5;

FIG. 9 is an exploded isometric view of the turntable and a base in which the turntable is rotatably mounted.

FIG. 10 is an isometric view of a latch for locking the turntable against rotation in the base;

FIG. 11 is an isometric view of the machine looking from the back of the machine;

FIG. 12 is an isometric view of the machine mounting the shaft for heightwise movement;

FIG. 13 is an isometric view of the mechanism for moving the roughing tool forwardly and rearwardly with respect to the housing;

FIG. 14 is an exploded isometric view of the shaft, the tines, the bar and the sensing finger;

FIG. 15 is an isometric view of the shaft and the tines mounted to the front of the shaft;

FIG. 16 is an isometric view of the sensing finger, the tines and the roughing tool;

FIG. 17 is an isometric view showing a control for effecting forward-rearward movement of the roughing tool with respect to the housing;

FIG. 18 is an isometric view of an arrangement mounting the roughing tool for heightwise movement in the tool mount;

FIG. 19 is a view of the lever and the valve mounted to the housing for controlling the rocking of the roughing tool;

FIG. 20 is a plan view of a part of the adjusting mechanism for effecting rearward movement of the roughing tool with respect to the housing;

FIG. 21 is a section showing the bar to whose front the sensing finger is mounted, the operating device, and part of the control interconnecting the bar and the motor for effecting foward-rearward movement of the roughing tool pursuant to the movement of the shoe assembly past the sensing finger;

FIG. 22 is a side elevation of a shoe assembly mounted in the machine;

FIG. 22A is a view taken along the line 22A—22A of FIG. 22;

FIG. 23 is a section showing the shoe assembly, the sensing finger, the tines and the roughing tool at the beginning of a roughing operation in the machine cycle;

FIG. 23A is a view taken along the line 23A—23A of FIG. 23;

FIG. 24 is a section of the toe portion of the shoe assembly;

FIG. 25 is an exploded isometric view of the sensing finger, the bar and a bracket mounting the sensing finger to the bar; and

FIG. 26 is a section taken along the line 26—26 of FIG. 25.

DESCRIPTION OF THE PREFERRED EMBODIMENT

The operator is intended to stand to the right of the machine as seen in FIG. 1. Directions extending toward the operator (left to right in FIG. 1) will be designated

as "forward" and directions extending away from the operator (right to left in FIG. 1) will be designated as "rearward." The front of the machine is closest to the operator and the back of the machine is furthermost away from the operator.

The machine, as shown in FIGS. 1 and 3, includes a shoe assembly mount section 10 and a tool section 12 located rearwardly of the section 10.

Referring to FIGS. 1, 3, 4 and 6, the section 10 includes a base 14 in which a turntable 16 is mounted for rotation in a horizontal plane. A slide 18 is slideably guided in the turntable 16 for reciprocating motion in a horizontal plane with respect to the turntable by means of gibs 20 that are secured to the turntable.

As shown in FIGS. 1 and 3, a post 22 rigidly mounted to the slide 18 and a last pin 24, that acts as a shoe assembly supporting element, extends upwardly of the post 22. An air operated motor 26, rigidly mounted to the post 22, has a piston rod 28 that is connected to a stand 30. The stand is slideably guided, by means of gibs 32, in slide 18 for reciprocating motion in a horizontal plane in directions that are parallel to the directions of reciprocating motion of the slide 18 in the turntable 16. An air operated motor 34, mounted to the stand 30, has a vertically movable piston rod 36. A toe pad 38, that acts as a shoe assembly supporting element, is affixed to the top of the piston rod 36. An air operated motor 40, mounted to the stand 30, has a piston rod 42 extending upwardly thereof. The piston rod 42 is secured to a strut 44 that is mounted to the stand 30 for heightwise movement. A bar 46 is pivoted by a pin 48 to the top of the strut 44 for swinging movement towards and away from the last pin 24. A toe stop 50 is rigidly mounted to the bar 46 and extends upwardly of the pin 48 so as to swing in unison with the bar 46. A cam 54 is mounted to the bottom of the bar 46 and is in intersecting relationship with a valve 56 that is affixed to the strut 44.

As shown in FIGS. 4, 5 and 7, a rack 58, mounted to the bottom of the slide 18, is in mesh with gear 60. The gear 60 is fixed to a shaft 62 that depends from the base 14 and is rotatably mounted in a collar 64 that is secured to the base 14. The collar 64 extends upwardly of the base 14 into the center of the turntable 16 and the center of the collar forms an axis about which the turntable is rotatable. A gear 66 is secured to the shaft 62 below the base 14 and, below the gear 66, the shaft 62 is affixed to an upper element of a pneumatically operated clutch 68 and extends through the lower element of the clutch 68.

A gear 70, secured to the turntable 16, is in mesh with a gear 72 that is rigidly mounted to a shaft 74. The shaft 74, which is rotatably mounted in and extends below the base 14, is affixed to an upper element of a pneumatically operated clutch 76 and extends through the lower element of the clutch 76.

The gear 66 is in mesh with a gear 78 that is rigidly mounted to a shaft 80. The shaft 80 is rotatably mounted in and extends below the base 14 and is affixed to an upper element of a pneumatically operated clutch 82.

A plate 84 is located below the base 14 and is secured to the base 14 by columns 86. A drive shaft 88, connected by a gear 90 to a source of power (not shown), is rotatably mounted in the plate 84 and is connected to a second element of the clutch 82. The bottoms of the shafts 62 and 74 are also rotatably mounted in the

plate 84. A sprocket 94 secured to the shaft 88 is drivingly connected by a chain 98 to a sprocket 96. The sprocket 96 is rotatably mounted to the shaft 62 and is secured to the lower element of the clutch 68. A sprocket 100 secured to the shaft 88 is drivingly connected by a chain 104 to a sprocket 102. The sprocket 102 is rotatably mounted to the shaft 74 and is secured to the lower element of the clutch 76.

Referring to FIGS. 4, 5 and 8, a shaft 106 extends through and is rotatably mounted in the shaft 62 and the clutch 68. An arm 108 is secured to the top of the shaft 106 and is located above the tops of the rack 58 and the gear 60. A cam 110 is secured to the bottom of the shaft 106 and is located below the plate 84. A tension spring 112, connected to and extending between the cam 110 and a clip 114 secured to the plate 84, yieldably urges the cam 110, together with the shaft 106 and the finger 108, about the axis of the shaft 106 to a position wherein the cam 110 abuts a pin 116 that is secured to and depends from the plate 84. A valve 118 is mounted to the plate 84 and is so located as to be actuated by the cam 110 when the cam 110 is moving about the axis of the shaft 106 and away from its position of abutment with the pin 116. A cam 120, having a radially projecting cam lobe 122, is mounted to the bottom of the shaft 74 below the plate 84. The cam lobe 122 is in intersecting relationship, during rotation of the shaft 74, with valves 124 and 126 that are mounted to the plate 84 and are located on opposite sides of the shaft 74.

Referring to FIG. 7, a finger 128 is mounted to the end of the slide 18 remote from the stand 30 and a finger 13 is mounted to the stand 30. The fingers 128 and 130 are located on opposite sides of the shaft 106 and are in intersecting relationship with the arm 108 during movement of the slide 18 with respect to the turntable 16 in the manner described below.

Referring to FIGS. 3, 9 and 10, a pair of recesses 132 are located in the periphery of the turntable 16 and are spaced 180 degrees apart. A latch 134 is pivotally mounted to the base 14 for swinging movement about a pin 136 into and out of intersecting relationship with respect to the recesses 132. The piston rod 138 of an air operated motor 140 is pivotally connected to the latch 134 to effect swinging movement of the latch 134 about the pin 136.

Referring to FIGS. 1-3 and 11, the tool section 12 includes a frame 142 in which an hydraulically operated motor 144 is mounted. The piston rod 146 of the motor 144 is connected to a slide 148 that is mounted for forward-rearward movement in the frame 142. Trunnions 150 (FIG. 12) on the slide 148 pivotally mount a yoke 152 for heightwise swinging movement about the horizontal axis of spindles 154 that are rigid with the yoke 152 and that are rotatably mounted in the trunnions 150. Air operated motors 158 are pivotally mounted on the slide 148 and have upwardly extending piston rods 160 that are pivotally connected to the yoke 152 to effect heightwise swinging movement of the yoke 152 about the axis of the spindles 154.

Referring to FIGS. 1, 2 and 11-13, a hollow shaft 162 extends forwardly and rearwardly through the yoke 152 and is so mounted in the yoke 152 that it is rotatable about its longitudinal axis but is fixed against forward-rearward movement in the yoke 152. As shown in FIGS. 14-16, a fork 164, having a pair of forwardly extending tines 166, is pivoted to a fork mount 167 that

is anchored to the front of the shaft 162 for heightwise swinging movement about the axis of pivot pins 168. An air actuated motor 170, mounted to an upwardly extending plate 172 of the fork 164, has a rearwardly directed piston rod 174 that is adapted to bear against a projection 176 on the fork mount 167 so as to swing the fork 164 about the axis of the pins 168 in a direction to move the tines 166 downwardly until a nozzle 178, mounted to a bracket 180 secured to the bottom of the fork 164, bears against a lower surface 182 on the bottom of the fork mount 167. A compression spring 184, interposed between the fork mount 167 and the fork 164, also acts to yieldably urge the fork 164 downwardly about the axis of the pins 168.

Referring to FIGS. 1-3, 11, 13 and 17, a housing 186 is rotatably mounted for swinging movement about the longitudinal axis of the shaft 162 by means of a front trunion 188 and a back trunion 190 that depend from the housing and are mounted to the shaft 162 for swinging movement about the shaft but are locked against forward-rearward movement lengthwise of the shaft. An hydraulically operated motor 192 is secured to a flange 194 that is rigid with one of the spindles 154. The piston rod 196 of the motor 192 is pivoted to the back of the housing 186 whereby the motor 192 may effect lateral swinging of the housing 186 about the axis of the shaft 162.

Referring to FIGS. 13 and 17, a tool mount or brush unit mount in the form of a yoke 198 is pivotally mounted, by pivot pins 200, to the front trunion 188 for forward-rearward swinging movement about the axis of the pins 200. An hydraulically actuated motor 202, that is pivotally mounted to the housing 186, has a forwardly directed piston rod 203 that is pivoted to the yoke 198 whereby the motor 202 may effect forward-rearward movement of the yoke 198 about the axis of the pins 200.

Referring to FIGS. 1, 13, 17 and 18, a block 204 is rigidly mounted to the yoke 198. A hollow sleeve 206 extends between the block 204 on one side of the yoke 198 and a projection 208 on the other side of the yoke 198. A brush unit 210 is pivotally mounted on the sleeve 206 for heightwise movement. The piston rod 212 of an air operated motor 214 is pivoted on a pin 216 that is mounted to the front trunion 188. The piston rod 212 is slideable in a clevis 218 which pivotally mounts the cylinder 220 of the motor 214. The clevis 218 is rigidly connected to the brush unit 210. The operation of the motor 214 is effective to raise and lower the cylinder 220 to thereby raise and lower the brush unit 210 about the axis of the sleeve 206.

A roughing tool in the form of a wire brush 222 is so rotatably mounted to the front of the brush unit 210 that the bottom of the brush periphery is located proximate to and between the fork tines 166 (see FIG. 16). An electric motor 226 is rigidly mounted to the block 204. The motor 226 is drivingly connected by way of a pulley 228 (FIG. 1), a belt 230 and a pulley 232 to a pulley shaft 234 that is rotatably mounted in the hollow sleeve 206. The pulley shaft 234 is drivingly connected by way of a pulley 236, a belt 238 and a pulley 240 to the brush 222 so as to enable the motor 226 to rotate the brush 222.

Referring to FIGS. 13, 17 and 19, a cam 242 is affixed to the shaft 162 between the yoke 152 and the front trunion 188. A lever 244 is pivoted between its ends to flange 246 that is secured to the housing 186.

A valve 248, mounted to the flange 246, has a spool 250 that is movably mounted in the body of the valve for movement towards and away from the top of the lever 244. The valve spool 250 is yieldably urged against the top of the lever 244 by pressurized air entering the valve 248 by way of a hose 252. A cam follower 254, mounted to the bottom of the lever 244, is urged into engagement with the periphery of the cam 242 by the valve spool 250 under the influence of the pressurized air flowing through the hose 252. The valve 248 and the motor 192 are so connected to each other and to a source of hydraulic fluid as to form a servo follow up mechanism that is so constructed, in a known manner, that relative motion in one direction or the other of the valve spool 250 with respect to the body of the valve 248 causes a corresponding extent of motion in one direction or the other of the piston rod 196 with respect to the motor 192.

Referring to FIGS. 17 and 20, a bushing 256 is secured to a side of the housing 186. An extension 258 of the body of a valve 260 is slidably mounted for forward-rearward movement in the bushing 256. A tension spring 262, interposed between a clip 264 secured to the bushing 256 and a clip 266 secured to the valve 260, acts to yieldably urge the valve 260, together with the valve extension 258, forwardly until a cam follower 268 at the front of the valve extension 258 bears against a cam surface 269 of a cam 270. The cam 270 is pivoted forwardly of the cam surface 269 to a pin 272 that is mounted to the housing 186. Forwardly of the pin 272, the cam 270 is pivoted by a pin 274 to the top of a link 276. The bottom of the link 276 is pivoted by a pin 278 to a lug 280 that is secured to the block 204.

The valve spool 282 of the valve 260 is, as is conventional, mounted for reciprocable linear forward-rearward movement in the body of the valve 260 and the valve extension 258. A nipple 284, mounted to the valve extension 258, is in communication with the hollow interior of the valve extension 258 and with the forward end of the valve spool 282. The nipple 284 extends through a slot 286 in the bushing 256 so as to enable the nipple and a hose 288 mounted to the nipple to have forward-rearward movement with respect to the bushing 256. The hose 288 is connected to a source of air which flows through the nipple 284 and into the hollow interior of the valve extension 258 to thereby yieldably urge the valve spool 282 rearwardly. The rearward movement of the valve spool 282 is limited by engagement with a pin 290 that is mounted to an end of a lever 292. The lever 292 is pivoted between its ends by a pin 294 to the back of the housing 186. The end of the lever 292 remote from the pin 294 is in alignment with the piston rod 296 of a spring return air actuated motor 298 that is mounted to the housing 186. The piston rod 296 projects rearwardly of the motor 298 and is yieldably urged forwardly by the return spring of the motor 298.

The valve 260 and the motor 202 are so connected to each other and to the source of hydraulic fluid as to form a servo follow up mechanism so constituted that relative motion in one direction or the other of the spool 282 with respect to a median position in the body of the valve 260 causes a corresponding motion in one direction or the other of the piston rod 203 with respect to the motor 202.

Referring to FIGS. 14-16 and 21, a bar 300 is mounted within the shaft 162 for forward-rearward movement. A sensing finger 302 is mounted to the front of the bar 300 and is located below and between the fork tines 166. A cap 304 is counted to the back of the shaft 162 and the body of a valve 306 is rigidly secured to the cap 304. The valve 306 has a valve spool 308 that is reciprocally mounted in the body of the valve 306 for forward-rearward movement. The front of the valve spool 308 is in registry with the back of the bar 300. The valve spool 308 is yieldably urged rearwardly by a compression spring 310 that is interposed between the back of the body of the valve 306 and a flange 312 at the back of the valve spool. A cap 314 is secured to the back of the body of the valve 306 so as to encompass the back of the valve spool 308. A nipple 316 at the back of the cap 314 is connected to a source of pressurized air so that the air may overcome the force of the spring 310 and yieldably urge the valve spool 308 forwardly in the body of the valve 306.

The valve 306 and the motor 144 are so connected to each other and to the source of hydraulic fluid as to form a servo follow up mechanism so constituted that forward-rearward movement in one direction or the other of the valve spool 308 with respect to a median position in the body of the valve 306 causes corresponding motion in one direction or the other of the piston rod 146 with respect to the motor 144.

As shown in FIGS. 15 and 16, a shield 318 is mounted by springs 320 to the fork 164 so as to extend between the fork tines 166 and above the sensing finger 302.

In the idle condition of the machine: the piston rod 28 is projected out of the motor 26 to place the stand 30 and the parts carried thereby, including the toe pad 38, the toe stop 50 and the finger 130, relatively remote from the post 22 and the last pin 24; the piston rod 36 is retracted into the motor 34 to place the toe pad 38 in a lower position; the piston rod 42 is projected out of the motor 40 to place the toe stop 50 in a raised position; the cam 54 is spaced from the valve 56; the slide 18 is at one end of the turntable 16 with the finger 128 in engagement with the arm 108 and the cam 110 swung against the force of the spring 112 so that the valve 118 is open, the last pin 24 is in substantial alignment with the axis of rotation of the turntable 16, and the last pin 24 is in substantial forward-rearward alignment with the brush 222; the shaft 88 is rotating; the clutches 68, 76 and 82 are uncoupled so that the sprocket 96 is being rotated about the stationary shaft 62 by the sprocket 94, the sprocket 102 is being rotated about the stationary shaft 74 by the sprocket 100, and the shaft 80 is stationary; the cam lobe 122 on the shaft 74 is in the FIG. 8 position; the piston rod 138 is projected out of the motor 140 so that the latch 134 is swung inwardly about the pin 136 into a recess 132 of the turntable 16 to lock the turntable against rotation; there is no pressurized air entering the cap 314 through the nipple 316 so that the spring 310 is forcing the valve spool 308 to a rearward position in the body of the valve 306 thereby causing the follow up servo central mechanism connecting the valve 306 and the motor 144 to retract the piston rod 146 into the motor 144 and thus place the slide 148, together with the brush unit 210, in a rearward position; the piston rods 160 are projected out of the motors 158 to place the brush unit 210 in an upper position; the spring 184 is

urging the fork 164 counterclockwise (FIG. 14) about the axis of the pins 168 to thereby urge the tines 166 downwardly to a position wherein the tip 321 of the top of the nozzle 178 abuts the surface 182; the piston rod 174 is projected rearwardly out of the motor 170 to a position close to but spaced from the projection 176; pressurized air is entering the body of the valve 248 through the hose 252 to yieldably urge the valve spool 250 leftwardly (FIG. 19) against the top of the lever 244 while the cam 242 is causing the lever 244 to push the valve spool 250 to a median position in the body of the valve 248 to thereby cause the servo follow up mechanism connecting the valve 248 and the motor 192 to maintain the piston rod 196 in a median position in the motor 192 so that the fork tines 166 are in a substantially horizontal plane and the axis of rotation 322 (FIG. 13) of the pulley 240 and of the brush 222 is in a substantially horizontal plane; the motor 298 is projecting the piston rod 296 rearwardly to thus cause the pin 290 to push the valve spool 282 forwardly of the body of the valve 260 against the force of the pressurized air that is entering the hollow interior of the valve extension 258 through the hose 288 and the nipple 284 to thus cause the servo follow up mechanism between the valve 260 and the motor 202 to project the piston rod 203 forwardly of the motor 202 so as to cause the brush unit 210 to be in a forward position with respect to the front trunion 188 so that the brush 222 is in a relatively forward position with respect to the fork tines 166; the spring 262 is yieldably urging the valve 260 forwardly to bring the valve extension 268 into abutment with the cam surface 269; the cylinder 220 is projected upwardly of the piston rod 212 to maintain the brush unit 210 in an upper position with respect to the block 204 to thus position the brush 222 in a relatively elevated position with respect to the fork tines 166; and the electric motor 226 is operative to rotate the brush 222.

FIGS. 22 and 22A show a shoe assembly that comprises a last 324 having an upper 326 mounted thereon and an insole 328 located at its bottom. The upper 326 has been lasted so that the upper margin 330 lies against and is secured to the insole and extends inwardly of the periphery of the insole and of the last bottom.

The shoe assembly is mounted by the operator bottom-up on the last pin 24, with the last pin entering the conventional thimble hole in the top of the heel portion of the last, in such a manner that the toe end of the shoe assembly faces the stand 30. The operator then manually operates a valve (not shown) to so actuate the motor 26 as to cause the piston rod 28 to be retracted into the motor 26 so as to move the stand 30, together with the toe pad 38, the toe stop 50 and the finger 130, towards the post 22 under the yieldable force of pressurized air until the toe stop 50 engages the toe end of the shoe assembly. This engagement causes the bar 46 and the toe stop 50 to swing clockwise (FIG. 1) about the axis of the pin 48 to thus cause the cam 54 to intersect and shift the valve 56. The shifting of the valve 56 actuates the motors 34 and 40 so that the motor 34 raises the toe pad 38 and the motor 40 lowers the bar 46 and the toe stop 50.

Referring to FIG. 3A, the toe stop 50, on the opposite side of the toe stop from the bar 46, has a depending prong 332 that is pivoted on the pin 48 and that is yieldably urged away from the post 22 and against a stop

334 that is fixed to the strut 44 by a spring 336 to maintain the toe stop 50 and the cam 54 in their idle positions. The swinging of the toe stop about the axis of the pin 48 swings the prong 332 so as to bring it into alignment with a guide 338 mounted to the stand 30. The prong 332 engages the guide 338 during the descent of the toe stop 50 to thus retain the toe stop 50 and the bar 46 in their swung condition so that the valve 56 is retained in shifted condition by the cam 54 for the remainder of the machine cycle.

The lowering of the toe stop 50 removes it from the periphery of the toe end of the shoe assembly so that it will not interfere with the roughing operation described below. The raising of the toe pad 38 under the yieldable force of pressurized air enables it to engage the forepart of the shoe assembly and tilt it about the last pin 24 until the last pin engages the periphery of the thimble hole in the last 324, thereby locking the shoe assembly to the slide 18 for the below described roughing operation.

FIG. 6 shows a pair of air hoses 340 and 342 that are mounted to the collar 64. The hose 340 is in communication with a passage 344 in the collar 64 and the passage 344 is in communication with an annular groove 346 in the collar 64. The groove 346 is in communication with a passage 348 in the turntable 16 and the passage 348 is in communication with an air hose 350 that is mounted to the turntable 16. The hose 342 is in communication with a passage 352 in the collar 64 and the passage 352 is in communication with an annular groove 354 in the collar 64. The groove 354 is in communication with a passage 356 in the turntable 16 and the passage 356 is in communication with an air hose 358 that is mounted to the turntable 16. One of the hoses 350 and 358 directs pressurized air to the motors 26, 34 and 40 to retain them in their idle conditions and the other of these hoses directs pressurized air to the motors 26, 34 and 40 to actuate these motors as described above. The arrangement shown in FIG. 6 enables the motor 26, 34 and 40 to remain in actuated condition when the turntable 16 is rotated as described below.

After the shoe assembly has been locked to the slide 18, the operator momentarily pulses a valve (not shown) to concomitantly actuate the motors 158 to retract the piston rods 160 into these motors and to send pressurized air into the nipple 316. The actuation of the motors 158 causes them to lower the shaft 162 to lower the brush unit 210 and the fork tines 166 about the axis of the spindles 154 under the yieldable force of the pressurized air actuating the motors 158. The admission of pressurized air to the nipple 316 acts as operating means to move the valve spool 308 forwardly with respect to the body of the valve 306 against the force of the spring 310 to thereby move the bar 300 and the sensing finger 302 forwardly. This forward movement, by means of the servo follow up mechanism connecting the valve 306 and the motor 144, actuates the motor 144 to project its piston rod 146 forwardly to thus move the slide 148, together with the brush unit 210 and the fork tines 166, forwardly.

The downward movement of the brush unit 210 and the fork tines 166 is terminated when the fork tines 166 engage the upper margin 330 in one of its breast line regions (see FIG. 23) which causes the fork 164 to swing clockwise (FIG. 14) about the axis of the pins 168 against the force of the springs 184 until the piston

rod 174 engages the projection 176. The forward movement of the brush unit 210 and the fork tines 166 is terminated when the sensing finger 302 engages the side of the shoe assembly and then moves rearwardly in the shaft 162 to move the valve spool 308 rearwardly in the valve body 306 against the force of the pressurized air in the cap 314 until the valve spool reaches a median position in the valve body. The arrival of the valve spool in the median position, caused by the arrival of the bar 300 in a median position in the shaft 162, enables the servo follow up mechanism connecting the valve 306 and the motor 144 to terminate forward movement of the piston rod 146.

The nozzle 178 (FIG. 16) has a passage 360 extending therethrough that is in communication with conduits in the form of air hoses 362 and 364. In the idle condition of the machine, the nozzle tip 321 is blocked by the surface 182 and pressurized air is flowing from a source through the hose 362 and into the passage 360. Since the top of the passage 360 is blocked by the surface 182, the pressurized air flows from the passage 362 through the hose 364 to pilot a spring return valve (not shown) so as to shift this valve. The clockwise swinging of the fork 164 (FIG. 14) about the axis of the pins 168 pursuant to the engagement of the fork tines 166 with the upper margin 330 causes the nozzle tip 321 to be spaced from the surface 182 so that air flowing into the passage 360 may flow out of the nozzle tip 321 to thereby diminish or terminate the flow of air in the hose 364 to thus enable the return spring of the valve associated with the hose 364 to shift this valve.

The shifting of the valve associated with the hose 364 acts as triggering means to cause the motor 214 to be so actuated as to lower the cylinder 220 under the force 35 of pressurized air to thereby swing the brush unit 210 downwardly about the axis of the sleeve 206 until the bristles 368 on the brush 222 engage the upper margin 330 between the fork tines 166 (see FIGS. 23 and 23A). The shifting of the valve associated with the hose 364 also actuates the motor 140 to swing the latch 134 away from the recess 132 with which it had been in engagement to unlock the turntable 16 for rotation and actuate the clutch 76 to couple the rotating sprocket 102 to the shaft 74 to thereby rotate the shaft 74. The rotation of the shaft 74, by way of the gears 70 and 72, effects rotation of the turntable 16 about the axis of the collar 64 to thus rotate the slide 18 and the shoe assembly about a center that is substantially in alignment with the last pin 24 and that lies approximately at the center of curvature, indicated by number 370 in FIG. 22A, of the heel portion of the bottom of the shoe assembly.

From the foregoing, it can be seen that the engagement of the fork tines 166 with the upper margin 330 causes a concomitant lowering of the rotating brush 222 into engagement with the upper margin 330 and a movement of the heel portion of the upper margin past the rotating brush. This arrangement enables the bristles 368 of the rotating brush 222 to abrade or rough the upper margin 330 as it is moving past the brush. If the brush were in engagement with the upper margin 330 while the shoe assembly was stationary it would gouge an undesirable groove in the upper margin which is avoided by concomitantly lowering the brush into engagement with the upper margin and commencing the movement of the upper margin past the brush.

During the movement of the heel portion of the upper margin past the roughing brush 222, as well as

the other portions of the upper margin as described below, the brush must move upwardly or downwardly in accordance with the elevation of the portion of the upper margin being roughed and must move forwardly and rearwardly so as to be positioned the desired distance inwardly of the portion of the outer periphery of the upper margin 330 being roughed. In addition, the central plane of the brush 222 which is at right angles to its axis of rotation, indicated by the chain line 372 in FIG. 23A, should be tilted during the movement of the portions of the upper margin being roughed past the roughing brush 222 so as to be at right angles to the plane of the portion of the upper margin 330 being roughed.

The upward and downward movement of the brush 222 during the movement of the upper margin past the brush is accomplished by virtue of the fact that the brush is mounted to partake of the swinging movement of the yoke 152 and is thus resiliently urged downwardly by the air operated motors 158.

The forward and rearward movement of the brush 222 during the movement of the upper margin past the brush is accomplished by the sensing finger 302 which is being resiliently urged forwardly against the side of the shoe assembly by the pressurized air in the cap 314. The servo follow up mechanism connecting the valve 306 and the motor 144 is so constituted that the piston rod 146 is stationary to maintain the brush position stationary in forward-rearward directions when the valve spool 308 is in a median position in the body of the valve 306 and the bar 300 is thus in a median position in the shaft 162. A forward movement of the sensing finger 302 by a portion of the side of the shoe assembly being displaced from the sensing finger causes the valve spool 308 to move forwardly in the body of the valve 306 to thereby cause the associated servo follow up mechanism to so operate the motor 144 as to move the piston rod 146 forwardly and thus move the brush 222 and the sensing finger 302 forwardly until the sensing finger 302 again engages the side of the shoe assembly and thereby causes the bar 300 to move the valve spool 308 into its median position in the body of the valve 306. A rearward movement of the sensing finger caused by a rearward pushing of the sensing finger by a portion of the side of the shoe assembly causes the bar 300 to move rearwardly of its median position in the shaft 162 to push valve spool 308 rearwardly in the body of the valve 306 to thereby cause the associated servo follow up mechanism to so operate the motor 144 as to move the piston rod 146 rearwardly and thus move the brush 222 and the sensing finger 302 rearwardly until the side of the shoe assembly stops pushing the sensing finger rearwardly so that the valve spool 308 regains its median position in the body of the valve 306.

The tilting of the central plane 372 of the brush 222 is accomplished by the mounting of the fork tines 166, together with the housing 186, for rotation about the axis of the shaft 162. During the movement of the upper margin 300 past the fork tines 166 that are being yieldably urged downwardly against the upper margin, the tines swing about the axis of the shaft 162 so that a plane connecting the bottom of the tines is parallel to the plane of the upper margin engaged by the tines. This causes the cam 242 to swing one way or the other and thus, through the lever 244, effect movement of the valve spool 250 one way or the other from a median

position in the body of the valve 248. A movement of the valve spool 250 in one direction or the other from its median position in the body of the valve 248 enables the servo follow up mechanism interconnecting the valve 248 and the motor 192 to cause the motor 192 to move the piston rod 196 in a direction to swing the housing 186 one way or the other until the valve spool 250 is again in its median position in the body of the valve 248. The swinging of the housing 186 in a particular direction cause the brush 222 to be swung in a corresponding direction until its central plane 372 lies in a plane at right angles to the plane of the bottoms of the fork tines 166.

As the shoe assembly rotates about the axis 370, the finger 128 becomes disengaged from the arm 108, thus enabling the spring 112 to cause the cam 110 to close the valve 118. When the shaft 74 has rotated 180° from its starting position shown in FIG. 8, the cam 122, momentarily pulses the valve 126 to momentarily open the valve 126. The momentary opening of the valve 126 actuates the pneumatic clutch 82 so as to couple the shaft 80 for rotation in unison with the shaft 88. The momentary opening of the valve 126 also causes the clutch 76 to be deactuated to thereby terminate the rotation of the shaft 74 and thus terminate the rotation of the turntable 16. The momentary opening of the valve 126 also actuates the motor 140 to swing the latch 134 into engagement with a recess 132 to thus lock the turntable 16 against rotation. From the foregoing, it can be seen that, after the turntable 16 has been rotated 180 degrees to enable the heel portion of the upper margin 330 from one breast line portion to the other breast line portion to be roughed by the tool 222, the turntable 16, together with the shoe assembly, ceases its rotation and is locked against rotation and the shaft 80 is caused to rotate. The rotation of the shaft 80, by means of the gears 66, 78, causes the shaft 62 to rotate to thus rotate the gear 60 in a direction to move the rack 58, together with the slide 18 and the shoe assembly, lengthwise past the brush 222 so that the brush 222 engages a first side portion 374 (FIG. 22A) of the upper margin 330 as the shoe assembly moves in a heel to toe direction past the brush 222 and the brush 222 thus roughs the first side portion 374 of the upper margin 330. This lengthwise movement of the shoe assembly in a heel to toe direction past the brush 222 continues until the finger 130 engages the arm 108 which is in intersecting relationship with the finger 130 due to the aforementioned disengagement of the finger 128 from the arm 108 during the rotation of the shoe assembly about the axis 370.

The aforementioned movement of the finger 130 towards the post 22 by the motor 26 continued until the toe stop 50 engaged the toe end of the shoe assembly and placed the finger 130 in a position wherein the approximate center of curvature of the toe portion of the shoe assembly, indicated by number 376 in FIG. 22A, is in registry with the axis of rotation of the turntable 16, formed by the center of the collar 64, when the slide 18 completes its lengthwise movement on the stationary turntable 16 and the shoe assembly completes its movement in a heel to toe direction past the brush 222. The engagement of the arm 108 by the finger 130 causes the cam 110 to open the valve 118.

The opening of the valve 118 causes the motor 140 to swing the latch 134 away from the recess 132 it had engaged to unlock the turntable for rotation. The opening of the valve 118 also deactuates the clutch 82 to

terminate the lengthwise movement of the slide 18 and of the shoe assembly in the turntable 16 and actuates the clutch 76 to again cause rotation of the turntable 16, the turntable now rotating about the point 376 so that the toe portion of the upper margin 330 is swung past the brush 222 and is roughed.

As shown, somewhat exaggeratedly, in FIG. 24, the bottom of the shoe assembly in its toe portion is somewhat rounded and upwardly convex while the bottom of the shoe assembly is relatively horizontal in a cross-section taken from side to side of the shoe assembly in the non-toe portion of the shoe assembly as shown in FIG. 23. Therefore, in the toe portion of the shoe assembly, the bottom of the shoe assembly slopes upwardly as it extends inwardly of the shoe assembly periphery. Up to now in the machine cycle, the fork tines 166 had been maintained substantially horizontal by the abutment of the piston rod 174 against the projection 176 and the brush 222 had been placed in a relatively forward position with respect to the sensing finger 302 by the motor 202 so that the fork tines would bear flushly against the upper margin 330 during the movement of the upper margin past the fork tines and so that the brush bristles 368 would engage and rough the upper margin 330 a desired distance inwardly of the upper margin periphery. However, due to the inward and upward inclination of the upper margin 330 in the toe portion of the shoe assembly, this relatively forward position of the brush with respect to the sensing finger 302 would cause the brush bristles 368 to engage the upper margin further inwardly of the upper margin periphery than it does in the non-toe portion of the shoe assembly. In order to overcome this difficulty and to enable the fork tines 166 to continue to bear flushly against the upper margin 330 in the toe portion of the shoe assembly, the brush 222 is moved rearwardly relative to the sensing finger 302 by adjusting means and the fork tines are enabled to swing upwardly about the axis of the pins 168 by adjusting means in the manner described below during the movement of the toe portion of the shoe assembly past the brush in the manner described below.

The opening of the valve 118 by the finger 130 also causes the venting of the motor 170 so that the yieldable downward force imparted to the fork 164 against the shoe assembly by the motors 158 causes the fork 164 to swing upwardly about the axis of the pins 168 with the piston rod 174 retracting into the motor 170 until the fork tines 166 lie in a plane substantially parallel to the surface of the upper margin 330 against which they are bearing.

The opening of the valve 118 by the finger 130 also vents the motor 298 so that the return spring of this motor retracts the piston rod 296 forwardly into this motor to thereby move the pin 290 rearwardly of the valve spool 282. This enables the pressurized air entering the interior of the valve extension 258 through the hose 288 to move the valve spool 282 rearwardly until it again engages the pin 290. This rearward movement of the valve spool moves it from its median position in the body of the valve 260 and thereby, by way of the servo follow up mechanism interconnecting the valve 260 and the motor 202, causes the motor 202 to move its piston rod 203 rearwardly to thereby move the brush unit yoke 198 and the block 204, together with the brush 222, rearwardly about the axis of the pins 200. This rearward movement of the block 204 causes the

link 276 to descend which causes the cam 270 to ascend about the axis of the pin 272. The cam surface 269 has a gradually increasing radius, from its top to its bottom, about the axis of the pin 272. The ascent of the cam 270 therefore causes the cam surface 269 to push the cam follower 268, together with the valve extension 258 and the body of the valve 260, rearwardly until the valve spool 282 is again in a median position in the body of the valve 260 to thereby cause the motor 202 to terminate the rearward movement of the piston rod 203 and of the brush 222.

As the shoe assembly rotates about the axis 376, the finger 130 becomes disengaged from the arm 108, thus enabling the spring 112 to cause the cam 110 to close the valve 118. When the shaft 74 has rotated 180 degrees from its starting position to swing the toe portion of the upper margin 330 through a 180 degree arc past the brush 222, the cam 122 momentarily pulses the valve 124 to momentarily open the valve 124.

20 The momentary opening of the valve 124 causes the clutch 76 to be deactivated and causes the motor 140 to swing the latch 134 into engagement with the recess 132 to thereby terminate the rotation of the turntable 16 and to lock the turntable against rotation.

25 The momentary opening of the valve 124 also reactivates the motor 298 to cause the piston rod 296 to be projected rearwardly and thus cause the pin 290 to move the valve spool 282 forwardly of its median position in the body of the valve 260 against the force of the pressurized air flowing through the hose 288. The follow up servo control mechanism interconnecting the valve 260 and the motor 202 causes the motor 202 to move the piston rod 203 forwardly in response to the forward movement of the valve spool 282. The forward movement of the piston rod 202 causes the brush yoke 198 and the block 204, together with the brush 222, to move forwardly about the axis of the pins 200. This forward movement of the block 204 causes the link 276 to ascend which causes the cam 270 to descend about the axis of the pin 272. The descent of the cam 270 causes the cam surface 269 to retreat from the cam follower 268. The cam follower 268, together with the body of the cam 270, are caused to move forwardly to follow the retreating cam surface 269 by the spring 262 until the valve spool 282 is again in a median position in the body of the valve 260 to thereby cause the motor 202 to terminate the forward movement of the piston rod 203 and of the brush 222 with the brush 222 now in its original forward position with respect to the sensing finger 302.

30 The momentary opening of the valve 124 also actuates the motor 170 to project its piston rod 174 rearwardly against the projection 176 to thereby cause the fork 164 to swing downwardly about the axis of the pins 168 and thus lower the fork tines 166 to bring them again into a position wherein their bottoms again lie in a substantially horizontal plane.

35 The momentary opening of the valve 124 also actuates the pneumatic clutch 68 to couple the rotating sprocket 96 to the shaft 62 to thereby rotate the shaft 62 and to cause the gear 60 to rotate in the opposite direction from which it was previously rotated in response to the actuation of the clutch 82. This rotation of the gear 62 moves the rack 58, together with the slide 18 and the shoe assembly, lengthwise past the brush 222 so that the brush 222 engages the second side portion 378 (FIG. 22A) of the upper margin 330 as the shoe

40 45 50 55 60 65

assembly moves in a toe to heel direction past the brush 222 and the brush 222 thus roughs the second side portion 378 of the shoe assembly. The lengthwise movement of the shoe assembly in a toe to heel direction of the brush 222 continues until the finger 128 engages the arm 108 which is in intersecting relationship with the finger 128 due to the aforementioned disengagement of the finger 130 from the arm 108 during the rotation of the shoe assembly about the axis 376. The engagement of the arm 108 by the finger 128 causes the cam 110 to again open the valve 118.

This opening of the valve 118 causes the deactuation of the clutch 68 to terminate the toe and heel movement of the shoe assembly past the brush 222 and causes the machine parts to return their idle positions and complete the machine cycle. The shoe assembly, with the roughed upper margin, is now removed from the machine.

During the rotation of the turntable 16 about the points 370 and 376, there should be no relative movement between the rack 58 and the gear 60 so that the slide 18 will be stationary with respect to the turntable. The engagement of the teeth of the rack 58 and the gear 60 is usually sufficient to preclude this relative movement. However, if desired, the appropriate clutch 68 or 82 may be actuated during one or the other of these rotations to positively rotate the gear 60 in the direction appropriate to preclude this relative movement.

The shield 318 protects the sensing finger from the brush bristles 368 during the machine operation.

With some shoe assemblies it is desired to not rough a portion of the upper margin such as the heel portion. In this event, the machine is so controlled as to not lower the brush 222 into engagement with the upper margin when the portion of the upper margin that is not to be roughed is being moved past the brush 222.

Referring to FIG. 25, it can be seen that the sensing finger 302 is mounted to the bar 300 by means of a bracket 380 interposed between the sensing finger and the bar. The bracket 380 has a notch 382 in its rear that is engaged by a hook 384 at the front of the bar 300. The sensing finger has an arcuate depending flange 386 (FIG. 26) that is slideably guided in an arcuate groove 388 in the front of the bracket 380. The center of curvature of the flange 386 and the groove 388 coincides with the forwardmost end 390 of the concavely curved front of the sensing finger 302. Therefore, as the sensing finger follows the contour of the curved side of the shoe assembly, during the movement of the shoe assembly past the the sensing finger, the sensing finger can pivot about its forwardmost end to ensure that its forwardmost end is always in engagement with the side of the shoe assembly. This arrangement causes the motor 144 to so move the slide 148 together with the brush 222 forwardly and rearwardly as to insure that the brush is engaging the upper margin 330 a constance distance inwardly of the periphery of the upper margin.

As can be seen in FIG. 26, the bottom of the finger 302 slopes upwardly and forwardly to thus insure that the forwardmost end 390 of the sensing finger engage the side of the shoe assembly close to its bottom (its upper end as seen in FIG. 23).

I claim:

1. A machine for roughing the margin of an upper of a shoe assembly, said shoe assembly comprising a last

having an insole located on its bottom and the upper mounted thereon with the upper margin lying against and being secured to the periphery of the insole, comprising: a shoe assembly support for supporting the shoe assembly bottom-up; a frame located rearwardly of the shoe assembly support; a slide mounted to the frame for forward-rearward movement; a first motor connected to the slide for effecting said forward-rearward movement; a yoke mounted to the slide for heightwise movement; a second, yieldable, motor connected to the yoke for effecting its heightwise movement; a shaft mounted to the yoke for rotation about a forward-rearward axis and extending forwardly of the yoke; a tine mounted to the front of the shaft; a housing mounted to the shaft for swinging movement about the shaft axis; a third motor connected to the housing for effecting its swinging movement; a tool mount mounted to the housing for swinging movement therewith; a roughing tool mounted to the tool mount for heightwise movement and located proximate to said tine; a fourth, yieldable, motor connected to said roughing tool for effecting its heightwise movement with respect to the tool mount; a bar mounted to the shaft for forward-rearward movement; a sensing finger mounted to the front of the bar and located below the tine; operating means actuatable to yieldably urge the bar forwardly of a median position with respect to the shaft; a first control so interconnecting the bar and the first motor as to cause the first motor to move the slide forwardly when the bar is forward of said median position and to move the slide rearwardly when the bar is rearward of said median position; a second control so interconnecting the shaft and the third motor as to be operative in response to the rotation of the shaft about its axis with respect to the yoke a particular amount in a particular direction to cause the third motor to swing the housing about the axis of the shaft a corresponding amount in said particular direction; means for initially causing the first motor to maintain the slide in a rearward position; means for initially causing the second motor to maintain the yoke in an upper position; means for initially causing the fourth motor to maintain the roughing tool in an upper position with respect to said tool mount; means for initially deactuating said operating means; means for thereafter actuating said operating means and for causing the second motor to lower the yoke to thereby move the sensing finger into engagement with the side of the shoe assembly and to thereby bring the tine into engagement with a portion of the upper margin; and means for thereafter causing the fourth motor to lower the roughing tool with respect to said tool mount into engagement with said portion of the upper margin and for so moving the shoe assembly support with respect to the roughing tool as to move other portions of the upper margin past the roughing tool.

2. The machine as defined in claim 1 further comprising: triggering means responsive to the engagement of the tine with said portion of the upper margin to cause the fourth motor to lower the roughing tool as aforesaid and to move the shoe assembly support as aforesaid.

3. The machine as defined in claim 2 further comprising: a tine mount anchored to the front of the shaft; means mounting the tine to the tine mount for heightwise movement; and means yieldably urging the tine downwardly with respect to the tine mount into an initial tine position, said tine moving upwardly with respect to the tine mount from said initial tine position

pursuant to the engagement of the tine with said upper portion; and wherein said triggering means comprises: a nozzle, having a tip, so mounted that the tip is in engagement with a surface of the tine mount when the tine is in said initial tine position and the tip is spaced from said surface when the tine is moved upwardly from said initial tine position; a passage in the nozzle intersecting the nozzle tip; a first conduit and a second conduit in communication with the passage; means for forcing air through the first conduit that flows through the second conduit when the passage is blocked by the engagement of the nozzle tip with said surface and whose flow is diminished when the nozzle tip is spaced from said surface; and means responsive to said diminution of air flow through the second conduit to cause the fourth motor to lower the roughing tool as aforesaid and to move the shoe assembly support as aforesaid.

4. The machine as defined in claim 1 wherein said first control comprises: a valve, having a valve body and a valve spool moveable forwardly and rearwardly in the valve body, mounted to the back of the shaft rearwardly of the bar with the valve spool abutting the back of the bar; and means so connecting the valve and the first motor to move the slide forwardly when the valve spool is forward of a median valve spool position in the valve body and to cause the first motor to move the slide rearwardly when the valve spool is rearward of said median valve spool position; wherein said means for deactuating said operating means comprises: spring means yieldably urging the valve spool rearwardly of said median valve spool position; and wherein said operating means comprises: means for overcoming said spring means and yieldably urging the valve spool forwardly of said median valve spool position.

5. The machine as defined in claim 4 wherein said operating means further comprises: a cap secured to and extending rearwardly of the valve body so as to encompass the back of the valve spool; and a nipple in the cap connected to a source of pressurized air.

6. The machine according to claim 1 wherein said second control comprises: a cam mounted to the shaft; a valve, having a valve body and a valve spool movable in the valve body, mounted to the housing; means so connecting the valve and the third motor as to cause the third motor to swing the housing in opposite directions about the shaft axis when the valve spool is moved in corresponding directions from a median position in the valve body; a lever, pivoted to the housing, having a first end bearing against the cam and a second end bearing against the valve spool; and means yieldably urging the valve spool against said second lever end.

7. The machine according to claim 1 further comprising: a tine mount anchored to the front of the shaft; means pivoting the tine to the tine mount for swinging movement about a prone axis that is transverse to said shaft axis so that the tine extends forwardly of said prone axis; restraining means normally restraining the tine on the tine mount in a lower position with respect to the tine mount; means mounting the tool mount to the housing for forward-rearward movement; a fifth motor connected to the tool mount for effecting the forward-rearward movement of the tool mount with respect to the housing; means for normally causing the fifth motor to retain the tool mount in a forward position with respect to the housing; first adjusting means effective, when a particular portion of the upper margin is being moved by the shoe assembly support past

the roughing tool, to release the restraining means so as to enable the tine to swing about said prone axis so that it extends upwardly and forwardly of said lower position from said prone axis; and second adjusting means, effective concomitantly with the first adjusting means, to cause the fifth motor to move the tool mount rearwardly to a rearward position with respect to the housing.

8. The machine according to claim 7 wherein said restraining means comprises: a rod mounted to the tine for forward-rearward movement; and a projection on the tine mount located rearwardly of the rod; wherein the means normally restraining the tine on the tine mount in said lower position comprises: means for applying a force to the rod to force the rod rearwardly against the projection; and wherein said first adjusting means comprises: means releasing the application of said force to the rod.

9. The machine according to claim 7 further comprising: a valve, having a valve body and a valve spool moveable in the valve body, mounted to the housing; means so connecting the valve and the fifth motor as to cause the fifth motor to move the tool mount rearwardly when the valve spool is displaced in a particular direction from a median position in the valve body; wherein the means for normally causing the fifth motor to retain the tool mount in said forward position comprises: means for normally retaining the valve spool in said median position; and wherein said second adjusting means comprises: means for imparting such relative movement between the valve spool and the valve body as to displace the valve spool in said particular direction with respect to the valve body and for thereafter imparting such a relative movement between the valve body and the valve spool as to return the valve spool to said median position.

10. A machine for roughing the margin of an upper of a shoe assembly, said shoe assembly comprising a last having an insole located on its bottom and the upper mounted thereon with the upper margin lying against and being secured to the periphery of the insole, comprising: a shoe assembly support for supporting the shoe assembly bottom-up; a frame located rearwardly of the shoe assembly support; a slide mounted to the frame for forward-rearward movement; a motor connected to the slide for effecting said forward-rearward movement; a roughing tool mounted to the slide for heightwise movement with respect to the slide and for forward-rearward movement in unison with the slide; a bar mounted to the slide for forward-rearward movement; a sensing finger mounted to the front of the bar; operating means actuatable to yieldably urge the bar forwardly of a median position with respect to the slide; a control so interconnecting the bar and the motor as to cause the motor to move the slide forwardly when the bar is forward of said median position and to move the slide rearwardly when the bar is rearward of said median position; means for initially causing the motor to maintain the slide in a rearward position; means for initially maintaining the roughing tool in an upper position with respect to the slide; means for initially deactuating said operating means; means for thereafter actuating said operating means to thereby cause the motor to move the sensing finger into engagement with the side of the shoe assembly and for lowering the roughing tool into engagement with a portion of the upper margin; and means for thereafter so moving the shoe as

sembly support with respect to the roughing tool as to move other portions of the upper margin past the roughing tool.

11. The machine as defined in claim 10 wherein said control comprises: a valve, having a valve body and a valve spool movable forwardly and rearwardly in the valve body, mounted to the back of the shaft rearwardly of the bar with the valve spool abutting the back of the bar; and means so connecting the valve and the first motor as to cause the first motor to move the slide forwardly when the valve spool is forward of a median valve spool position in the valve body and to cause the first motor to move the slide rearwardly when the valve spool is rearward of said median valve spool position; wherein said means for deactuating said operating means comprises: spring means yieldably urging the valve spool rearwardly of said median valve spool position; and wherein said operating means comprises: means for overcoming said spring means and yieldably urging the valve spool forwardly of said median valve spool position.

12. The machine as defined in claim 11 wherein said operating means further comprises: a cap secured to and extending rearwardly of the valve body so as to encompass to back of the valve spool; and a nipple in the cap connected to a source of pressurized air.

13. A machine for roughing the margin of an upper of a shoe assembly, said shoe assembly comprising a last having an insole located on its bottom and the upper mounted thereon with the upper margin lying against and being secured to the periphery of the insole, comprising: a shoe assembly support for supporting the shoe assembly bottom-up; a frame located rearwardly of the shoe assembly support; a shaft mounted to the frame for heightwise movement; a first, yieldable, motor connected to the shaft for effecting its heightwise movement; a tine mounted to the front of the shaft; a tool mount mounted to the shaft; a roughing tool mounted to the tool mount for heightwise movement and located proximate to said tine; a second, yieldable, motor connected to said roughing tool for effecting its heightwise movement with respect to the tool mount; means for initially causing the first motor to maintain the shaft in an upper position; means for initially causing the second motor to maintain the roughing tool in an upper position with respect to said tool mount above the tine; means for thereafter causing the first motor to lower the shaft to thereby bring the tine into engagement with a portion of the upper margin; and means for thereafter causing the second motor to lower the roughing tool with respect to said tool mount into engagement with said portion of the upper margin and for so moving the shoe assembly support with respect to the roughing tool as to move other portions of the upper margin past the roughing tool.

14. The machine as defined in claim 13 further comprising: triggering means responsive to the engagement of the tine with said portion of the upper margin to cause the second motor to lower the roughing tool as aforesaid and to move the shoe assembly support as aforesaid.

15. The machine as defined in claim 14 further comprising: a tine mount anchored to the front of the shaft; means mounting the tine to the tine mount for heightwise movement; and means yieldably urging the tine downwardly with respect to the tine mount into an initial tine position, said tine moving upwardly with re-

spect to the tine mount from said initial tine position pursuant to the engagement of the tine with said upper portion; and wherein said triggering means comprises: a nozzle, having a tip, so mounted that the tip is in engagement with a surface of the tine mount when the tine is in said initial position and the tip is spaced from said surface when the tine is moved upwardly from said initial tine position; a passage in the nozzle intersecting the nozzle tip; a first conduit and a second conduit in communication with the passage; means for forcing air through the first conduit that flows through the second conduit when the passage is blocked by the engagement of the nozzle tip with said surface and whose flow is diminished when the nozzle tip is spaced from said surface; and means responsive to said diminution of air flow through the second conduit to cause the second motor to lower the roughing tool as aforesaid and to move the shoe assembly support as aforesaid.

16. A machine for roughing the margin of an upper of a shoe assembly, said shoe assembly comprising a last having an insole located on its bottom and the upper mounted thereon with the upper margin lying against and being secured to the periphery of the insole, comprising: a shoe assembly support for supporting the shoe assembly bottom-up; a frame located rearwardly of the shoe assembly support; a shaft mounted to the frame for rotation about a forward-rearward axis; a tine mounted to the front of the shaft; a housing mounted to the shaft for swinging movement about the shaft axis; a motor connected to the housing for effecting its swinging movement; a roughing tool, mounted to the housing for swinging movement in unison therewith, located proximate to said tine; a cam mounted to the shaft; a valve, having a valve body and a valve spool movable in the valve body, mounted to the housing; means so connecting the valve and the motor as to cause the motor to swing the housing in opposite directions about the shaft axis when the valve spool is moved in corresponding directions from a median position in the valve body; a lever, pivoted to the housing, having a first end bearing against the cam and a second end bearing against the valve spool; means yieldably urging the valve spool against said second lever end; and means for imparting such relative movement between the shoe assembly support and the tine as to move portions of the upper margin past the tine with the roughing tool bearing against and roughing the upper margin portions.

17. A machine for roughing the margin of an upper of a shoe assembly, said shoe assembly comprising a last having an insole located on its bottom and the upper mounted thereon with the upper margin lying against and being secured to the periphery of the insole, comprising: a frame; a housing mounted to the frame for forward-rearward movement and for heightwise movement; a roughing tool mounted to the housing for forward-rearward movement; a sensing finger, located below the roughing tool, mounted for heightwise movement in unison with the housing and mounted for forward-rearward movement; a shoe assembly support, located forwardly of the frame, for supporting the shoe assembly bottom-up; means for yieldably urging the housing downwardly so as to bring the roughing tool into engagement with a portion of the upper margin and for yieldably urging the sensing finger forwardly to bring it into engagement with a corresponding portion of the side of the shoe assembly;

means for normally maintaining the roughing tool in a forward position with respect to the housing; means for so moving the shoe support as to move other portions of the upper margin past the roughing tool and other corresponding portions of the side of the shoe assembly past the sensing finger; means so connecting the sensing finger and the housing as to enable forward and rearward movements of the sensing finger while it is bearing against succeeding portions of the side of the shoe assembly to impart corresponding forward and rearward movements to the housing; and adjusting means, effective when a particular portion of the upper margin is being moved by the shoe assembly support past the roughing tool, to move the roughing tool rearwardly with respect to the housing.

18. A machine as defined in claim 17 wherein the means for moving the shoe assembly support comprises: a turntable mounted for rotary movement about an upright axis; a slide mounted to the turntable for reciprocal movement in two opposite directions between two end positions on the turntable; means for mounting the shoe assembly support to the slide; means for first moving the slide with respect to the turntable, while the turntable is stationary, in a first of said directions between said end positions to enable the roughing tool to rough a first side portion of the upper margin; means for thereafter moving the slide with respect to the turntable, while the turntable is stationary, in the other of said directions between said end positions to enable the roughing tool to rough the other side portion of the upper margin; and means for rotating the turntable, while the slide is stationary and is located at one end of said positions and between said movements of the slide with respect to the turntable, to enable the roughing tool to rough the toe portion of the upper margin; and further comprising: means to render both of said adjusting means effective during rotation of the turntable.

19. The machine according to claim 17 further comprising: a tine mount mounted for heightwise and forward-rearward movement in unison with the housing; a tine pivoted to the tine mount for swinging movement about a prone axis that is transverse to a forward-rearward direction, said tine being located proximate to said roughing tool and engaging the upper margin when the roughing tool engages the upper margin pursuant to said downward urging of the housing; restraining means normally restraining the tine on the tine mount in a lower position with respect to the tine mount; and second adjusting means, effective concomitantly with the first mentioned adjusting means, to release the restraining means so as to enable the tine to swing about said prone axis so that it extends upwardly and forwardly of said lower position from said prone axis.

20. A machine as defined in claim 19 wherein the means for moving the shoe assembly support comprises: a turntable mounted for rotary movement about an upright axis; a slide mounted to the turntable for reciprocal movement in two opposite directions between two end positions on the turntable; means for mounting the shoe assembly support to the slide; means for first moving the slide with respect to the turntable, while the turntable is stationary, in a first of said directions between said end positions to enable the roughing tool to rough a first side portion of the upper margin; means for thereafter moving the slide with respect to the turntable, while the turntable is stationary, in the other of

said directions between said end positions to enable the roughing tool to rough the other side portion of the upper margin; and means for rotating the turntable, while the slide is stationary and is located at one of said end positions and between said movements of the slide with respect to the turntable, to enable the roughing tool to rough the toe portion of the upper margin; and further comprising: means to render both of said adjusting means effective during rotation of the turntable.

21. A machine for roughing the margin of an upper of a shoe assembly, said shoe assembly comprising a last having an insole located on its bottom and the upper mounted thereon with the upper margin lying against and being secured to the periphery of the insole, comprising: a shoe assembly support for supporting the shoe assembly bottom-up; a frame located rearwardly of the shoe assembly support; a slide mounted to the frame for forward-rearward movement; a first motor connected to the slide for effecting said forward-rearward movement; a shaft mounted to the slide for heightwise movement; a second, yieldable, motor connected to the shaft for effecting its heightwise movement; a tine mount anchored to the front of the shaft; a tine pivoted to the tine mount for swinging movement about a prone axis that is transverse to a forward-rearward direction; restraining means normally restraining the tine on the tine mount in a lower position with respect to the tine mount; a tool mount mounted to the shaft for forward-rearward movement; a third motor connected to the tool mount for effecting the forward-rearward movement of the tool mount with respect to the shaft; means for normally causing the third motor to retain the tool mount in a forward position with respect to the shaft; a roughing tool mounted to the tool mount for heightwise movement and located proximate to said tine; a fourth, yieldable, motor connected to said roughing tool for effecting its heightwise movement with respect to the tool mount; a bar mounted to the shaft for forward-rearward movement; a sensing finger mounted to the front of the bar and located below the tine; operating means actuatable to yieldably urge the bar forwardly of a median position with respect to the shaft; a control so interconnecting the bar and the first motor as to cause the first motor to move the slide forwardly when the bar is forward of said median position and to move the slide rearwardly when the bar is rearward of said median position; means for initially causing the first motor to maintain the slide in a rearward position; means for initially causing the second motor to maintain the shaft in an upper position; means for initially causing the fourth motor to maintain the roughing tool in an upper position with respect to said tool mount; means for initially deactuating said operating means; means for thereafter concomitantly actuating said operating means and for causing the second motor to lower the shaft to thereby move the sensing finger into engagement with the side of the shoe assembly and to thereby bring the tine into engagement with a portion of the upper margin; means for thereafter causing the fourth motor to lower the roughing tool with respect to said tool mount into engagement with said portion of the upper margin and for so moving the shoe assembly support with respect to the roughing tool as to move other portions of the upper margin past the roughing tool; first adjusting means effective, when a particular portion of the upper

margin is being moved by the shoe assembly support past the roughing tool, to release the restraining means so as to enable the tine to swing about said prone axis so that it extends upwardly and forwardly of said lower position from said prone axis; and second adjusting means, effective concomitantly with the first adjusting means, to cause the third motor to move the tool mount rearwardly to a rearward portion with respect to the shaft.

22. A machine as defined in claim 21 wherein the means for moving the shoe assembly support comprises: a turntable mounted for rotary movement about an upright axis; a support slide mounted to the turntable for reciprocal movement in two opposite prone directions between two end positions on the turntable; means mounting the shoe assembly support to the support slide; means for first moving the support slide with respect to the turntable, while the turntable is stationary, in a first of said directions between said end positions to enable the roughing tool to rough a first side portion of the upper margin; means for thereafter moving the support slide with respect to the turntable, while the turntable is stationary, in the other of said directions between said end positions to enable the roughing tool to rough the other side portion of the upper margin; and means for rotating the turntable, while the slide is stationary and is located at one end of said end positions and between said movements of the slide with respect to the turntable, to enable the roughing tool to rough the toe portion of the upper margin; and further comprising: means to render both of said adjusting means effective during the rotation of the turntable.

23. The machine according to claim 21 wherein said restraining means comprises: a rod mounted to the tine for forward-rearward movement; and a projection on the tine mount located rearwardly of the rod; wherein the means normally restraining the tine on the tine mount in said lower position comprises: means for applying a force to the rod to force the rod rearwardly against the projection; and wherein said first adjusting means comprises: means releasing the application of said force to the rod.

24. The machine according to claim 21 further comprising: a valve, having a valve body and a valve spool movable in the valve body, mounted to the shaft; means so connecting the valve and the third motor as to cause the third motor to move the tool mount rearwardly when the valve spool is displaced in a particular direction from a median position in the valve body; wherein the means for normally causing the third motor to retain the tool mount in said forward position comprises: means for normally retaining the valve spool in said median position; and wherein said second adjusting means comprises: means for imparting such relative movement between the valve spool and the valve body as to displace the valve spool in said particular direction with respect to the valve body and for thereafter imparting such relative movement between the valve body and the valve spool as to return the valve spool to said median position.

25. A machine for roughing the margin of a shoe assembly said shoe assembly comprising a last having an insole located on its bottom and the upper mounted thereon with the upper margin lying against and being secured to the periphery of the insole, comprising: a turntable mounted for rotation about an upright axis; a slide mounted to the turntable for reciprocal move-

ment in two opposite prone directions between two end positions on the turntable; a shoe assembly support mounted to the slide adapted to support the shoe assembly bottom-up; adjusting means cooperative with the shoe assembly for adjusting the spacing between said end positions an amount that is proportional to the length of the shoe assembly that is supported on the support; means for rotating the turntable 180 degrees in the same direction while the slide is stationary in each of said end positions; means for moving the slide between each of said end positions to the other of said end positions while the turntable is stationary after the completion of each of said rotations of the turntable; a roughing tool so located that the upper margin portions move past the roughing tool during said rotations of the turntable and during said movements of the slide between said end positions; and means for enabling the roughing tool to engage the upper margin portions during the movement of at least some of said upper margin portions past the roughing tool.

26. The machine as defined in claim 25 wherein said adjusting means comprises: a post rigidly mounted to the slide; a shoe assembly supporting element mounted to the post; a stand mounted to the slide for movement towards and away from the post; a shoe assembly supporting element mounted to the stand; means spacing the stand from the post a distance that is proportional to the length of the shoe assembly; actuating mechanisms mounted to the post and to the stand; and terminating means responsive to the arrival of each of said actuating mechanisms at a prescribed location in the turntable pursuant to said slide movements to terminate each of said slide movements.

27. The machine according to claim 26 wherein said actuating mechanisms comprise fingers mounted to the post and to the stand; and wherein said terminating means comprises: an arm mounted to the turntable in intersecting relationship with each of the fingers during the movement of each of the fingers toward the arm; and means responsive to the intersection of each finger with the arm to terminate a slide movement between said end position.

28. The machine as defined in claim 25 wherein said adjusting means comprises: a post rigidly mounted to the slide; a last pin, which acts as a shoe assembly supporting element, mounted to the post; a stand mounted to the slide for movement toward and away from the post; a toe pad, which acts as a shoe assembly supporting element, mounted to the stand; a toe stop mounted to the stand in intersecting relation to the toe end of the shoe assembly; yieldable drive means for moving the stand towards the post to thereby cause the toe stop to engage the toe end of a shoe assembly mounted to the last pin; means responsive to said engagement to lock the shoe assembly to said supporting elements and disengage the toe stop from the shoe assembly; actuating mechanisms mounted to the post and to the stand; and terminating means responsive to the arrival of each of said actuating mechanisms at a prescribed location in the turntable pursuant to said slide movements to terminate each of said slide movements.

29. The machine as defined in claim 28 further comprising: means mounting the toe pad for heightwise movement; means mounting the toe stop for heightwise movement; means for initially locating the toe pad in a lower position; means for initially locating the toe stop in an upper position; means responsive to said engage-

ment to lower the toe stop to thereby disengage the toe stop from the shoe assembly; and means responsive to said engagement to raise the toe pad into engagement with the shoe assembly to thereby lock the shoe assembly to said supporting elements.

30. The machine according to claim 28 wherein said actuating mechanisms comprise: fingers mounted to the post and to the stand; and wherein said terminating means comprises: an arm mounted to the turntable in intersecting relationship with each of the fingers during

the movement of each of the fingers towards the arm; and means responsive to the intersection of each finger with the arm to terminate a slide movement between said end positions.

5 **31.** The machine according to claim 10 wherein the sensing finger curves rearwardly of its forwardmost end and further comprising: means mounting the sensing finger to the bar for pivoting movement about said forwardmost end.
